UNITED STATES PATENT OFFICE.

ADDISON LANCE AND MADISON YOLTON, OF FRANKFORT SPRINGS, PA.

MOTOR.

SPECIFICATION forming part of Letters Patent No. 274,203, dated March 20, 1883.

Application filed February 9, 1883. (No model.)

To all whom it may concern:

Be it known that we, ADDISON LANCE and MADISON YOLTON, of Frankfort Springs, in the county of Beaver and State of Pennsylvania, have invented certain new and useful Improvements in Motors; and we do hereby declare that the following is a full, clear, and exact description of the invention, which will enable others skilled in the art to which it applies to make and use the same, reference being had to the accompanying drawings, which form a part of this specification, and in which—

Figure 1 is a perspective view of our improved motor. Fig. 2 is a detail view of the wheel upon the drive-shaft. Fig. 3 is a similar view of the pawl and spring upon the said wheel, and Fig. 4 is a similar view of the pitman in the motor.

Similar letters of reference indicate corresponding parts in all the figures.

Our invention has relation to motors for operating churning, and for other domestic purposes; and it consists in the improved construction and combination of parts of such a motor operated by a weight, as hereinafter more fully described and claimed.

In the accompanying drawings, the letter A indicates the frame of the motor, forming bearings for the several shafts, and B a tall box or tower in which the driving-weight travels. The driving-weight C is attached to one end of a cord or chain, D, which is carried over a pulley, E, in the top of the box, and down around and fastened to a drum, F, upon the drive-shaft G, which turns in bearings in the frame. The one end of the drum F is provided with a ratchet-wheel, H, which is engaged by a pawl, I, pivoted upon the face of the drive-wheel J. The back of the pawl I is grooved longitudinally at K for the reception of the flat rounded free end L of a spring, M, which is fastened to the face of the drive-wheel. The drive-wheel is journaled loose upon shaft G, so that the shaft and the drum may be rotated in winding the weight up without rotating the drive-wheel, the pawl I slipping over the inclined side of the ratchet-teeth; but when the weight acts upon the cord, turning the drum and shaft in an opposite direction, the ratchet-teeth engage with the pawl and turn that and the wheel with it.

To wind the cord upon the drum, hoisting the weight, a removable crank, N, is fitted upon the square end O of the drive-shaft. The drive-wheel J is brought to bear with its face against the face of the ratchet-wheel, so as to bring the pawl in a plane with the ratchet-teeth, by a plate or collar, P, having three, or more or less, spring-lips, Q, which are bent against and bear against the face of the wheel, the collar being held upon the shaft by a pin, R, a nut, or other suitable fastening. The cogs of the drive-wheel engage a pinion, S, fastened upon a shaft, T, upon which a cog-wheel, U, is fastened, which engages a pinion, V, upon the crank-shaft W. Upon the end of this shaft, which is journaled in bearings in the frame, as also shaft T is, is a fly-wheel, X, and the middle of the shaft is bent to form a double crank, Y. A pitman, Z, is pivoted to this crank and to the end of a lever, a, which is pivoted upon the frame, and with the other end of which the several devices which it is desired to operate may be connected. Pitman Z consists of an iron bar bent to form a series of eyes, b, having a small opening, c, at one side, as shown in Fig. 4, which enables the pitman to be changed upon the crank from one eye to another, the springiness of the iron allowing them to be slipped over the crank-pin, so that the end of the lever may be raised or lowered to suit machines of different height.

It will be seen that by having the drive-wheel sliding loose upon the drive-shaft, and held against the face of the ratchet-wheel, so that the pawl upon it may engage the latter, it may be slid to a side, so that the pawl is disengaged by pressing it against the spring-lips Q, which will allow the weight to run down without operating the machine, when it is desired to stop the same.

Having thus described our invention, we claim and desire to secure by Letters Patent of the United States—

1. In a motor of the described class, the combination of the drive-wheel J, journaled loose upon shaft G, with the collar P, having spring-lips Q, bearing against the face of wheel J, and held in place upon shaft G by a pin or nut, as and for the purpose set forth.

2. In a motor of the described class, the combination of the ratchet-wheel H, fastened upon the drive-shaft G, drive-wheel J, jour-

naled and sliding upon shaft G, and having pawl I grooved upon its back at K, and spring M, having flat rounded free end L, sliding in groove K, fastened upon its inner face, and 5 collar P, having spring-lips Q, bearing against the outer face of wheel J, and held in place upon shaft G by a pin or nut, as and for the purpose shown and set forth.

3. The pitman Z, consisting of a metallic 10 rod bent to form eyes b, having opening c, as and for the purpose shown and set forth.

4. The combination, in a motor of the de-

scribed class, of the crank Y with the lever a, having pitman Z, bent to form eyes b, having openings c, as and for the purpose shown and 15 set forth.

In testimony that we claim the foregoing as our own we have hereunto affixed our signatures in presence of two witnesses.

ADDISON LANCE.
MADISON YOLTON.
